BAROMETRIC DRAFT REGULATOR

Edward A. Field, Mendota, Ill.

Application September 29, 1950, Serial No. 187,492

17 Claims. (Cl. 236—45)

1

This invention relates to improvements in barometric draft regulators.

The main objects of this invention are: First, to provide an improved draft regulator for heaters and the like adapted to be attached to the smoke flue thereof to control the heater draft and down drafts, thereby particularly adapting the regulator for gas burners in which the down draft may either extinguish the gas flame or create improper combustion conditions so that carbon monoxide is produced.

Second, to provide a draft regulator of the above type in which the down draft is bypassed through the regulator to prevent extinguishment of the gas flame and creation of improper combustion conditions.

Third, to provide a regulator of the above type which may be readily and economically produced and installed and which is highly efficient in use.

Further objects relating to details and economies of the invention will appear from the description to follow. The invention is defined in the claims.

A structure which embodies the features of my invention is illustrated in the accompanying drawing, wherein:

Fig. 1 is a plan view of the regulator installed on the smoke flue with portions shown in section on the line 1—1 of Fig. 2.

Fig. 2 is an end view of the regulator applied to the flue.

Fig. 3 is an enlarged fragmentary perspective view showing the pivotal connection between the control gate and the supporting ring therefor.

Fig. 4 is an enlarged fragmentary sectional view on the line 4—4 of Fig. 5, viewed in the direction of the arrows.

Fig. 5 is a view, partially in side elevation and partially in vertical section, of the draft control ring and assembly, the gate being shown in full lines when closed and in dotted outline when opened outwardly due to a down draft.

Fig. 6 is a view in side elevation of the ring and gate assembly with parts broken away to show the portion of the gate when opened inwardly due to an updraft.

Figs. 7 to 10 inclusive illustrate a second embodiment of the invention, Fig. 7 showing in side elevation the gate assembly and associated parts, the relative position of the parts being shown when the gate is closed.

Fig. 8 is an enlarged fragmentary view in perspective of a detail of the gate assembly showing the relative position of the parts when the gate is subject to a down draft.

2

Fig. 9 is an enlarged fragmentary view in side elevation of a detail of the gate assembly showing the relative position of the parts when the gate is subject to an updraft.

Fig. 10 is an enlarged view showing the pivotal connection of the gate to the housing, the gate and the pivot member being shown in section.

The present invention relates to an automatic draft control particularly adapted for gas burners for controlling both up and down drafts. Since a gas fire can be extinguished rather easily by a down draft, it is essential, unless the burner has a forced draft, that some means be provided to bypass the down draft. A down draft can extinguish the flame or create such combustion conditions that carbon monoxide is produced.

If carbon monoxide escapes into the boiler or furnace room, even in rather small quantities, the result can be dangerous. It is the purpose of the present invention to provide a draft control which controls the updraft and bypasses down drafts to prevent the same from extinguishing the gas flame and creating such improper combustion conditions.

Referring to the embodiment of the invention illustrated in Figs. 1 to 6 inclusive, 1 designates the smoke flue and 2 a collar mounted on the side of the flue. A ring 3 constituting a gate housing is telescoped within the outer end of the collar.

The ring is provided with inwardly projecting recesses 4 on the opposite sides thereof for a purpose later described. A rod 5 secured to the opposite sides of the ring reinforces the same against distortion. Pins or studs 6 secured to the ring 3 constitute stops engaging the outer edge of the collar to limit inward movement of the ring.

A member 7 in the form of a segment is spot-welded or otherwise secured, as by brackets 8, to the ring at the top and adjacent the front thereof. This segment facilitates a better draft when there is an updraft and reduces tendency for gases to escape into the room, as later described.

A control gate 9 is pivotally mounted in the ring or gate housing adjacent the front end 45 thereof and beneath the segment 7. The upper part of the gate is cut away so as to swing by the segment 7 without interference. The upper and lower portions 10 and 11 of the gate are bent inwardly slightly to improve the regulating ability of the unit. Because the gate is pivoted above center, it is desirable that these portions be bent rearwardly. An angle member 12 riveted to the front side of the gate and projecting beyond the opposite side edges thereof is provided with knife edges 13 on the lower edges of its projecting end

50

55

edges 13 on the lower edges of its projecting end

portions. These knife edges pivotally engage at the bottom of V-shaped recesses in laterally projecting members 14 of bracket members 15 secured by means of bolts 16 to the outer sides of the ring 3 as shown more clearly in Fig. 3. This provides means for pivotally supporting the gate within the ring or gate housing. The recesses 4 in the ring 3 receive the projecting ends of the angle member 12. The gate beneath knife edges 13 is provided with recesses 17 to receive therein the gate supporting members 14, and the members 14 are provided with recesses 18 to receive therein edge portions of the gate. This construction prevents the gate from being lifted out of place.

Weights 19 and 20 are attached to the gate by means of a screw or threaded rod 21, as is old in the art. In addition, there is a disc 22 eccentrically attached by means of a screw 23 to the back side of the gate with the major portion of the disc disposed below the pivotal axis of the gate, as shown in dotted outline in Fig. 2. By means of these weights and the disc it is possible to bring the gate into essentially a static balance, though the center of gravity of the entire assembly is purposely located just a fraction of an inch below the pivot center line provided by the knife edges 13. This tends to urge the gate to a vertical closed position. A channel shaped member 24 is secured to the back of the gate to stiffen the same.

Weights 25 in the form of washers are supported on the horizontal inwardly bent portion 26 of the lever 27. A cotter pin 28 retains the washers in position on the lever. The lever has a horizontally inwardly projecting portion 29 adjacent the upper end thereof providing a shaft-like member extending through rearwardly bent ears 30 on the members 31. These bearing members are bolted to one of the projecting ends of the knife edge member 12. The lever 27 at the inner end of the bearing portion 29 thereof is bent upwardly to provide an arm 32 disposed for engagement by the horizontal flange 33 extending along the upper edge of the angle member 12 when the gate is in closed position as shown in full lines in Fig. 5. The arm 32 is also engaged by the flange 33 when the lower portion of the gate opens inwardly during an updraft. The lever 27 is loosely supported in the bearing members 31 to freely swing therein.

To limit the swinging movement of the lever 27 in the bearing members 31, stops 34 and 35 are provided. These stops are formed by outwardly bent portions on the bracket member 36 which is secured to the outer side of the gate housing by means of the bolts 16 which also secure one of pivot supporting brackets 15 to the gate housing. These stops are disposed in the path of movement of the horizontal arm 26 of the lever 27, the stop 34 limiting downward movement of the lever and the stop 35 limiting upward movement. The arm 32 of the lever being disposed in the path of movement of the flange 33 carried by the gate, the lever moves with the gate during inward movement of the lower portion of the gate caused by an updraft. This inward movement of both the gate and the lever is limited by engagement of the arm 26 of the lever with the stop 35. The gate has then opened inwardly through an angle of 65° from its closed position. The exact draft which the device maintains depends on the number of washers 25 on the lower end of the lever. The weights 19 and 20 are not changed after the unit leaves the factory.

In the event of a down draft, the lower part of the gate swings outwardly as shown in dotted outline in Fig. 5. The lever 27 and weights 25 then become inoperative in exerting a torque on the gate due to the arm 26 of the lever engaging the stop 34 and due to the flange 33 carried by the gate moving rearwardly away from the arm 32 of the lever. The only force which then tends to close the gate is the small force developed because the center of gravity of the gate assembly is located a minute distance below the pivotal axis of the gate.

A baffle 37 located in the flue passage 1 adjacent the opening of the flue into the collar 2 may be used to facilitate pressure against the inner side of the gate when there is a down draft in the chimney flue. The baffle is provided with a narrow edge portion 37a bent to incline in the direction of travel of the gases from the furnace 20 to the chimney and is provided with an ear 38 integral therewith and bent laterally thereof through which bolts 39 pass for attaching the baffle to the collar 2. If no baffle is used in the flue pipe, it will be possible to operate at higher drafts at the outlet of the furnace or boiler, as may possibly be desirable in some cases with certain types of gas burners. The draft regulator, though, will not be as effective in diverting a downdraft. For such higher drafts, when no baffle is used, the weights 25 are disposed at a greater angular distance from the vertical plane of the gate than the angular distance shown in Fig. 5. This may be readily effected by simply bending or twisting the lever 27 so that the weights 19 are disposed at greater angular distance from the vertical plane of the gate. The stops 34 and 35 must also be disposed at a greater angular distance from the vertical plane of the gate. Another bracket may be substituted for the bracket 36 with its stops disposed at such greater angular distance. Since this construction involves no more than a mere change in angular position of the weights 25 and stops 34 and 35 relative to the vertical plane of the gate, it is not shown.

The segment 7 previously described as improving the regulating ability of the control has another purpose. When a burner is first lighted and the chimney is cool, there is a brief interval 50 during which there is but little draft. The hot gases from the combustion chamber drift along the flue passage near the top of the passage, which sometimes tends to produce a tiny bit of pressure inside the draft control at the top, though there may be a small vacuum down near the bottom. Because the top part of the ring is closed off by means of the segment 7, there is less tendency for the gases to escape under pressure into the room. After a very brief interval, draft 60 is established in the chimney and the device begins to function as a normal draft regulator with the larger lower portion opening inwardly.

Referring to the embodiment of the invention shown in Figs. 7 to 10 inclusive, 40 designates the chimney flue having a collar 41 secured thereto and projecting downwardly therefrom instead of horizontally as in the embodiment previously described. Telescopingly mounted in the lower end of this collar is a ring or gate housing 42 in the outer or lower end of which is pivotally mounted a control gate 43 having an angle member 44 riveted or otherwise suitably secured to the inner face thereof as shown in Fig. 10. The opposite ends of this angle member project into 70 sector shape openings 45 in the opposite sides

of the gate housing. The V-shaped ends of these openings are disposed downwardly and pivotally supportingly engage knife edges on the lower edges of the angle member adjacent the ends thereof. The angle member is bent laterally at one end to provide an arm 46 projecting horizontally therefrom when the gate is in a closed horizontal position as shown in Fig. 7. A pin 47 fixedly secured to the end of this arm projects into aligned openings 48 of square shape formed in the depending arms 49 of an inverted U-shaped member 50 formed of sheet metal. The bight 51 of the loop of this member is recessed at 52 and is supportingly engaged by a bracket member 53 riveted to the side of the gate housing. A washer 54 constituting a weight is secured by means of a bolt 55 between the lower ends of the arms 49. Only one washer is shown but more may be provided depending upon the updraft desired. The square openings 48 have their diagonals disposed horizontally and vertically. When the gate is closed, the pin 47 is disposed in the upper end of the openings 48 and the member 50 with its weight 54 are supported on the bracket member 53. At this time the gate is held in a horizontal position by a system of weights corresponding to that above described for holding the gate 9 in a vertical closed position. The center of gravity of the entire gate assembly is located just a fraction of an inch below the knife edges of the angle member 44 so as to hold to the gate in a normal horizontal closed position.

An updraft in the chimney flue causes the side of the gate having the inwardly bent edge portion 56 to move upwardly into the dotted line position shown in Fig. 9. The pin 47 engaging the member 50 at the upper end of the openings 48 raises the member 50 with the washer 54 from supporting engagement with the bracket 53. The gate then opens inwardly against the closing torque of the member 50 and washer 54. In the event of a downdraft the pressure on the inside of the gate being greater than on the outside, the gate opens outwardly thereby bypassing the downdraft to prevent either extinguishment of the flame of the burner or improper combustion conditions. During such outward movement of the gate, the pin 47 moves downwardly in the openings 48 of the member 50, and the member 50 and washer 54 are supported entirely by the bracket 53, as shown in Fig. 8.

The controls of both embodiments above described are very sensitive in controlling the heater draft and in bypassing downdrafts. The controls may be readily and economically produced, installed and adjusted and are highly efficient throughout a long life.

I have illustrated and described my invention in embodiments which I have found very practical. I have not attempted to illustrate or describe other embodiments or adaptations as it is believed this disclosure will enable those skilled in the art to embody or adapt my invention as may be desired.

Having thus described my invention what I claim as new and desire to secure by Letters Patent is:

1. In a draft regulator device, an open ended gate housing, a pivotally mounted gate disposed in said housing for opening inwardly during an updraft and outwardly during a down draft, the pivotal axis of the gate being horizontal, weighting means on said gate, the center of gravity of the gate and weighting means being disposed vertically below the pivotal axis of the gate to

effect a closing torque on the gate, a lever pivotally supported intermediate its ends on said gate, the pivotal axis of the lever being horizontal, one of the arms of the lever extending above said pivotal axis of the lever and the other arm extending below said pivotal axis of the lever, a weight on the lower arm, means on said gate disposed above said pivotal axis of the gate for engaging the upper arm of the lever 10 when the gate opens inwardly due to an updraft, said lower arm and weight being disposed to move inwardly and upwardly by engagement of said means with said upper arm during such inward opening movement of the gate, and a stop supported on said gate housing and disposed to engage said lower arm and support said arm and weight inwardly of the gate in slightly inclined relation to the vertical plane of the gate when the gate is closed and opening outwardly due to a downdraft.

2. In a draft regulator device, an open ended gate housing, a pivotally mounted gate disposed in said housing for opening inwardly during an updraft and outwardly during a downdraft, the pivotal axis of the gate being horizontal, weighting means on said gate, the center of gravity of the gate and weighting means being disposed vertically below the pivotal axis of the gate to effect a closing torque on the gate, a lever pivotally supported intermediate its ends on said gate, the pivotal axis of the lever being horizontal, one of the arms of the lever extending above the axis of the lever and the other arm extending below said axis, a weight on the lower arm, and means on said gate disposed above the axis of the gate for engaging the upper arm of the lever when the gate opens inwardly due to an updraft, said lower arm and weight being disposed to move inwardly and upwardly by engagement of said means with said upper arm during such inward opening movement of the gate.

3. In a draft regulator, an open ended gate housing, a pivotally mounted gate disposed in said housing for opening inwardly during an updraft and outwardly during a downdraft, the pivotal axis of the gate being approximately horizontal, weighting means on said gate, the center of gravity of said gate and weighting means being disposed vertically below said pivotal axis to produce a closing torque on the gate, a lever pivotally supported on said gate, the pivotal axis of the lever being approximately horizontal, a weight on said lever disposed below its pivotal axis, means on said gate disposed to engage said lever 45 when the gate opens inwardly due to an updraft, said weight moving generally inwardly and upwardly by engagement of said means with said lever during such inwardly opening movement of the gate, and a stop supported by said gate housing and disposed to support said lever in inwardly inclined relation to the vertical plane of the gate when the gate is closed and opening outwardly due to a downdraft.

4. In a draft regulator, an open ended gate housing, a pivotally mounted gate disposed in said housing for opening inwardly during an updraft and outwardly during a downdraft, the pivotal axis of the gate being approximately horizontal, weighting means on said gate, the center of gravity of said gate and weighting means being disposed vertically below said pivotal axis to produce a closing torque on the gate, a lever pivotally supported on said gate, the pivotal axis of the lever being approximately horizontal, a weight on said lever disposed below its pivotal

axis, and means on said gate disposed to engage said lever when the gate opens inwardly due to an updraft, said weight moving generally inwardly and upwardly by engagement of said means with said lever during such inwardly opening movement of the gate to produce additional closing torque on the gate, said means on said gate being disengaged from said lever on outward movement of the gate due to a downdraft, whereby the gate opens outwardly against the closing torque only of said weighting means on said gate.

5. In a draft regulator, a gate housing, a pivotally mounted gate disposed in said housing for opening inwardly during an updraft and outwardly during a downdraft, a first means connected to said gate for producing a closing torque on the gate when opening either inwardly or outwardly and a second means for producing additional closing torque on the gate only when the gate is opened inwardly, said second means being disposed to be operated by inward opening movement of the gate, said second means including a lever and a weight supported thereby.

6. In a draft regulator for heaters having a smoke flue, a gate housing for attachment to a side of the flue and constituting a passageway between the flue and the outside atmosphere, a pivotally mounted gate disposed in said housing for opening inwardly for passage of atmospheric air into the flue at the side thereof during an updraft and outwardly for passage of flue gases out of the flue at the side thereof during a downdraft, said gate being weighted to produce a closing torque on the gate when opening either inwardly or outwardly, and means for producing additional closing torque on the gate only when the gate is opened inwardly, said means including a weight disposed to be raised by inward opening movement of the gate.

7. In a draft regulator, a gate housing, a pivotally mounted gate disposed in said housing for opening inwardly during an updraft and outwardly during a downdraft, a first means for producing a closing torque on the gate and a second means for producing closing torque on the gate only when the gate is opened inwardly, said second means being disposed to be operated by said gate when the gate is opened inwardly, said second means including a pivoted weighted member disposed for a swinging upward movement as the gate opens inwardly and means on said gate for swinging said member upwardly only during inward opening movement of the gate.

8. In a draft regulator for heaters having a smoke flue, a gate housing for attachment to a side of the flue and constituting a passageway between the flue and the outside atmosphere, a pivotally mounted gate disposed in said housing for opening inwardly for passage of atmospheric air into the flue at the side thereof during an updraft and outwardly for passage of flue gases out of the flue at the side thereof during a downdraft, said gate being weighted to produce a closing torque on the gate, and means for producing closing torque on the gate only when the gate is opened inwardly, said means being disposed to be operated by said gate when the gate is opened inwardly.

9. In combination, a smoke flue, an open ended housing mounted on said flue and projecting laterally from one of the sides thereof, the inner end of the housing opening to the flue and the outer end opening to the atmosphere, a pivotally mounted gate disposed in said housing for opening inwardly for passage of atmospheric air into

the flue at the side thereof during an updraft and outwardly for passage of flue gases out of the flue at the side thereof during a downdraft, means associated with said gate for producing a closing torque on the gate when opened either inwardly or outwardly, said means including means operable by the gate during an opening movement thereof for rendering the closing torque on the gate greater during its inward opening movement than during its outward opening movement.

10. In combination, a smoke flue, an open ended housing mounted on said flue, the inner end of the housing opening to the flue and the outer end opening to the atmosphere, a pivotally mounted gate disposed in the outer end of the housing for opening inwardly during an updraft and outwardly during a downdraft, and a baffle disposed in said smoke flue adjacent the inner end of said housing to deflect the gases passing through the flue into the housing and increase the pressure against the gate during a downdraft, the end portion of the baffle adjacent the housing being inclined in the direction of passage of the gases from the combustion chamber to the chimney.

11. In combination, a smoke flue, an open ended housing mounted on said flue, the inner end of the housing opening to the flue and the outer end opening to the atmosphere, a pivotally mounted gate disposed in the outer end of the housing for opening inwardly during an updraft and outwardly during a downdraft, and a baffle disposed in said smoke flue adjacent the inner end of said housing to deflect the gases passing through the flue into the housing and increase the pressure against the gate during a downdraft.

12. In a draft regulator, an open ended control housing, a pivotally mounted gate disposed in said housing for opening inwardly during an updraft and outwardly during a downdraft, and means for producing a closing torque on the gate operative on inward opening movement of the gate, said means comprising an inverted U-shaped member of sheet metal having aligned openings in the depending legs thereof, a weight disposed between and supported by said legs beneath said openings, a bracket member mounted on said housing for supportingly engaging said U-shaped member within the loop thereof when the gate opens outwardly, and an element operable by said gate and projecting into said openings, said element being disposed adjacent the top edges of said openings when the gate is closed, said element being disposed relative to the pivotal axis of the gate to raise the U-shaped member from supporting engagement with said bracket when the gate opens inwardly and disposed to move downwardly in said openings to permit the U-shaped member to be supported on said bracket when the gate opens outwardly.

13. In a draft regulator, an open ended control housing, a pivotally mounted gate disposed in said housing for opening inwardly during an updraft and outwardly during a downdraft, and means for producing a closing torque on the gate operative on inward opening movement of the gate, said means comprising an inverted U-shaped member having aligned openings in the depending legs thereof, a weight supported by said legs beneath said openings, a bracket member mounted on said housing for supportingly engaging said U-shaped member within the loop thereof when the gate opens outwardly, and an element operable by said gate and projecting into said openings, said element being disposed

adjacent the top edges of said openings when the gate is closed, said element being disposed relative to the pivotal axis of the gate to raise the U-shaped member from supporting engagement with said bracket when the gate opens inwardly and disposed to move downwardly in said openings to permit the U-shaped member to be supported on said bracket when the gate opens outwardly.

14. In a draft regulator, an open ended control housing, a pivotally mounted gate disposed in said housing for opening inwardly during an updraft and outwardly during a downdraft, and means for producing a closing torque on the gate when it opens inwardly comprising a weighted member, a bracket mounted on said housing for supporting said weighted member when the gate opens outwardly, and an element operable by said gate and disposed relative to the pivoted axis of the gate to raise said weighted element from supporting engagement with the bracket when the gate moves inwardly.

15. In a draft control, an open ended housing, a pivotally mounted gate disposed at the outer end of said housing for opening and closing movements, and means for pivotally supporting said gate on said housing comprising an elongated plate-like strip secured to said gate and having end portions disposed adjacent opposite side edges of the gate, said end portions having knife edges, and plate-like gate supporting members secured to the opposite sides of the housing and having depressed intermediate portions for supportingly receiving the knife edges of said strip, said gate supporting members having recesses in the portions thereof adjacent the edges of the gate to receive edge portions of the gate, said gate having recesses therein below the knife edges of the strip to receive the gate supporting members.

16. In a draft regulator, an open ended housing, a pivotally mounted gate disposed at the outer end of the housing for opening and closing movements, and means for pivotally supporting said gate on said housing comprising gate supporting members mounted on opposite sides of said housing and having depressed intermediate portions, and means on said gate pivotally engaged in the depressed portions of said supporting members for swingingly supporting the gate, said supporting members having recesses in portions thereof adjacent the edges of the gate for receiving edge portions of the gate.

17. In a draft regulator, an open ended control housing and a pivotally mounted gate disposed in the housing for opening inwardly during an updraft and outwardly during a downdraft, said gate having an outer swinging edge portion inclined inwardly to deflect the gases passing thereby during a downdraft to more widely open the gate and allow a greater volume of gases to escape.
